The ornamental design for a cervical pillow, as shown and described.

DESCRIPTION

FIG. 1 is a top perspective view of a first preferred embodiment of a cervical pillow of the present invention;
 FIG. 2 is a top plan view of the embodiment of FIG. 1;
 FIG. 3 is a side elevational view of the embodiment of FIG. 1;
 FIG. 4 is a cross-sectional view along lines 4—4 in FIG. 2;
 FIG. 5 is a front elevational view of the embodiment of FIG. 1;
 FIG. 6 is a cross-sectional view along lines 6—6 in FIG. 2;
 FIG. 7 is a top plan view of a second preferred embodiment of a cervical pillow of the present invention;
 FIG. 8 is a front elevational view of the embodiment of FIG. 7;
 FIG. 9 is a cross-sectional view along lines 9—9 of FIG. 7;
 FIG. 10 is a side elevational view of the embodiment of FIG. 7;
 FIG. 11 is a cross-sectional view along lines 11—11 of FIG. 7;
 FIG. 12 is a top plan view of a third preferred embodiment of a cervical pillow of the present invention;
 FIG. 13 is a side elevational view of the embodiment of FIG. 12;
 FIG. 14 is a cross-sectional view along lines 14—14 of FIG. 12;
 FIG. 15 is a front elevational view of the embodiment of FIG. 12; and,
 FIG. 16 is a cross-sectional view along lines 16—16 of FIG. 12.
